US00D617028S

(12) **United States Design Patent**
Verfuerth et al.

(10) **Patent No.:** **US D617,028 S**
(45) **Date of Patent:** **** Jun. 1, 2010**

(54) **LIGHTING FIXTURE**

(75) Inventors: **Neal R. Verfuerth**, Plymouth, WI (US); **Kenneth J. Wetenkamp**, Plymouth, WI (US); **Anthony J. Bartol**, Plymouth, WI (US); **Ronald E. Ernst**, Waldo, WI (US)

(73) Assignee: **Orion Energy Systems, Inc.**, Manitowoc, WI (US)

(**) Term: **14 Years**

(21) Appl. No.: **29/346,569**

(22) Filed: **Nov. 2, 2009**

Related U.S. Application Data

(62) Division of application No. 29/343,007, filed on Sep. 4, 2009, now Pat. No. Des. 606,697.

(57) **CLAIM**

We claim the ornamental design for a lighting fixture, as shown and described.

DESCRIPTION

FIG. 1 is a bottom perspective view of the claimed design; FIG. 2 is a top perspective view of the claimed design shown in FIG. 1;

FIG. 3 is a first side view of the claimed design shown in FIG. 1;

FIG. 4 is a second side view of the claimed design shown in FIG. 1;

FIG. 5 is a top view of the claimed design shown in FIG. 1; FIG. 6 is a bottom view of the claimed design shown in FIG. 1;

FIG. 7 is a front view of the claimed design shown in FIG. 1; and,

FIG. 8 is a rear view of the claimed design shown in FIG. 1. The ornamental design which is claimed is shown in solid lines in the figures. The broken lines in the figures illustrate portions of the lighting fixture which form no part of the claimed design.

1 Claim, 6 Drawing Sheets
